ADJUSTING AND INDICATING DEVICE FOR THE CAMS OF CIRCULAR KNITTING MACHINES Richard Schmidt, Hopfauerstrasse 49,
Stuttgart-Vaihingen, Germany

Filed Jan. 9, 1961, Ser. No. 81,427

Claims priority, application Germany Sept. 5, 1957
15 Claims. (Cl. 66—54)

The present invention relates to adjusting and indicating devices for the cams of a circular knitting machine, and more particularly to an arrangement in which at each station of the circular knitting machine, a first adjusting and indicating device is located on the cam box for adjusting the position of the raising and stitch cams, and for indicating the amount of displacement, and a second adjusting device is located on the dial cap for adjusting the position of the dial cam, and for indicating the displacement of the same.

The present application is a continuation-in-part application of my copending application Serial No. 758,240, filed on September 2, 1958, now abandoned.

The present invention is concerned with an improvement of a circular knitting machine of the type including a set of cylinder needles arranged on the needle cylinder, and a set of dial needles arranged on a dial plate in horizontal positions and cooperating with the cylinder needles. A dial cam is provided for advancing and retracting the dial needles, and a cylinder cam is provided on the cam box of the machine for raising and lowering the cylinder needles during rotation of the needle cylinder with the dial plate.

It is desirable to accurately adjust the dial cam means and cylinder cam means, and adjusting means are provided for this purpose.

In accordance with the present invention, a pair of adjusting and indicating devices is provided at each knitting station of the circular knitting machine, one adjusting device being provided for adjusting the radial position of the dial cam means, and the other adjusting device being provided for adjusting the position of the cylinder cam means, which include a raising cam and a stitch cam.

It is one object of the present invention to provide the adjusting devices with indicating means which face in the same direction so that they can be simultaneously inspected by the operator.

Another object of the present invention is to provide adjusting and indicating devices for the above explained purpose, which include first indicating means for indicating unit distances of the cam adjustments, and second indicating means for indicating fractions of the distance units.

Another object of the present invention is to provide such first and second indicating means on both adjusting devices at each knitting station, and to arrange all four indicating means to face in the same direction for simultaneous inspection by the operator.

Since adjusting devices are arranged at each knitting station of the machine spaced in circumferential direction from each other, it is also an object of the present invention to facilitate the inspection of the adjusting devices by the operator by providing all adjusting devices with indicating means which face outwardly.

With these objects in view, one embodiment of the present invention relates to a circular knitting machine and comprises first and second adjusting devices respectively connected to the dial cam means and the cylinder cam means of the knitting machine for respectively adjusting the position of the respective cam means. A pair of first and second adjusting devices is located at each knitting station in a radial plane passing through the main axis of the machine, and the indicating means of

2

the two adjusting devices at each station face in the same direction for simultaneous inspection.

Preferably, each adjusting device has first and second indicating means for respectively indicating distance units and fractions of distance units through which the respective cam means are displaced, or the first indicating means indicates degrees, and the second indicating means indicates full turns of the knob by which the device is manually controlled.

In the preferred embodiment of the present invention, one adjusting device is mounted on the dial cap, and has an operating knob, and a pair of indicating scales turnable about horizontal axes extending in radial direction of the machine. The other adjusting device is mounted on the cam box, and has a knob turnable about a vertical axis, and first and second cylindrical indicating scales turnable about the vertical axis and being visible through indicator windows located in a vertical plane parallel to the vertical plane in which the indicating means of the adjusting device on the dial cap are located. The vertical scales of all adjusting devices are located in an imaginary vertical cylinder having its axis coinciding with the axis of the machine, so that the operator, walking around the machine, can successively inspect all indicating means at a glance.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary axial sectional view illustrating the parts of a circular knitting machine to which the present invention is applied;

FIG. 2 is a fragmentary horizontal sectional view taken on line 2—2 in FIG. 1;

FIG. 3 is a fragmentary vertical sectional view on an enlarged scale showing an adjusting device mounted on the cam box of the machine, and taken on lines 3—3 in FIGS. 2 and 3a;

FIG. 3a is a fragmentary horizontal sectional view taken on line 3a—3a in FIG. 3;

FIG. 4 is a front elevation of the adjusting device shown in FIG. 3 as viewed in the direction of the arrow 4 in FIG. 3;

FIG. 5 is a vertical sectional view on an enlarged scale illustrating an adjusting device mounted on the dial cap of the knitting machine; and

FIG. 6 is a fragmentary front elevation of the adjusting device shown in FIG. 5.

Referring now to the drawings, and particularly to FIGS. 1 and 2, a needle cylinder 30 has on its outer cylindrical surface axially extending grooves in which the cylinder needles are guided for movement in vertical direction. Each cylinder needle has a butt 31a, and a hook and latch at its upper end for catching yarn supplied by feeding means, not shown. The dial plate or ring 32 has a horizontal top surface formed with radial grooves in which the dial needles 33 are guided for movement between advanced and retracted positions so as to cooperate with the cylinder needles 31. The dial needles 33 have butts 33a. The dial plate 32 and the needle cylinder 30 turn about a common vertical main axis so that the needles 31 move relative to the stationary annular cam box 38, and the dial needles 33 move relative to the stationary dial cap 46.

It will be understood that a plurality of yarn feeding means are arranged around the circumference of the machine, and each location where a feeding means is pro-

vided, is considered a knitting station. FIGS. 1 and 2 illustrate one of the knitting stations.

At each knitting station, cylinder cam means including a stitch cam 34a and the raising cam 34b are provided which together form a cam track for receiving the butts 31a of the cylinder needles. Dial cam means are mounted on the dial cap 46, and include an inner cam 42a, and an outer cam 42b. Cams 42a and 42b together form a cam track in which the butts 33a of the dial needles are guided. Since the cylinder needles 31 and dial needles 33 rotate with the needle cylinder, while the cam means are stationary, the needles will be moved in longitudinal direction into cooperating positions for forming a knitted fabric.

In order to determine the degree to which the dial needles are advanced, and the height to which the cylinder needles are raised, the cylinder cam means and dial cam means are adjustable.

The raising cam 34b and the stitch cam 34a are both secured by screws 36 to a carrier which includes a plate 35 slidably mounted in a vertical channel in the inner surface 38a, of the cam box 38, and a cylindrical rod 37 having a flattened face 37a abutting the rear face of plate 35. Screws 41 secure plate 35 to rod 37. A screw 39 is threaded into the cam box 38, and a spring 40 located in a recess 37b of rod 37 abuts screw 39 and urges the carrier 35, 37, together with the cam means 34a, 34b in upward direction until the upper end face of the carrier rod 37 abuts the bottom face of a member 5 of the adjusting means 100. As will be described hereinafter in greater detail, turning of the knob 1 of the adjusting means 100 will result in downward or upward movement of member 5, so that the position of the carrier and of the cylinder cams can be adjusted.

The dial cams 42a and 42b are secured by screws 43 to a carrier 44 slidably guided in a channel 45 of the dial cap 46 for radial movement. A screw 47 has a threaded portion threaded into carrier plate 44 to move with the same. The stem of screw 47 is located in an elongated slot 48 which permits radial movement of screw 47, but confines the same in circumferential direction of the dial cap 46. A spring 49 is located in recess 50 of dial cap 46, and urges screw 47, and thereby carrier 44 and cams 42a and 42b outwardly in radial direction until screw 47 abuts a threaded bolt 13 of an adjusting means 51 provided with a turnable knob 12a. Turning of knob 12a will effect axial movement of the threaded bolt 13 for shifting cam means 42a, 42b against the action of spring 49, as will be described hereinafter in greater detail with reference to FIGS. 5 and 6.

Referring now to FIGS. 3, 3a and 4, which illustrate the adjusting and indicating device 100, a bolt 2 has a first threaded portion 2a tightly screwed into a bushing 2' which is pressed into a corresponding bore in the cam box 38 so that bolt 2 is not turnable. Bolt 2 has a second threaded portion 2e, another stepped portion 2c, and a journal portion 2b provided with a threaded recess into which a screw 2d is threaded.

A turnable member 3 is mounted for turning movement on the stationary journal portion 2b, and includes a bearing sleeve 3a with a flange abutting the stepped portion 2c, a cylindrical ring 4, and a knob 1. Ring 4 is secured to the flange of sleeve 3a by a press fit, or by transverse screw passing through ring 4 into a threaded bore in the periphery of the flange of sleeve 3. The screw is not visible in FIG. 3. A pin 1a secures the knob 1 against turning movement on the bearing portion 3a of the turnable member 3, and is held in place by the head of screw 2d. A turnable threaded member 5 engages the threaded portion 2e of the stationary bolt 2, and has on the outside thereof axially extending guide projections cooperating with matching axially extending guideways in the inner cylindrical surface of the cylindrical ring 4. Consequently, members 1, 3, 4 and 5 are connected for turning movement, but member 5 will move in axial di-

rection when being turned on the threaded portion 2e. As best seen in FIGS. 1 and 2, the bottom face 5a of member 5 abuts the end face of the carrier rod 37, so that the carrier 35, 37 will be shifted in vertical direction when knob 1 is turned.

A pin 10 is urged by spring 10a against the bottom face 5a of member 5, and pin 10 is disposed at a diametrically opposite point in relation to carrier bolt 37 in order to prevent binding of the threaded part 5 due to the resistance of carrier rod 37 on one side of member 5.

A stationary casing member 6 has an annular part surrounding the bearing sleeve 3a, and a cylindrical casing part 6c which extends to knob 1 and into a matching recess in the top face of the cam box 38. A pin 9 is pressed into a bore of the cam box, and projects into a corresponding opening in the cylindrical casing portion 6c so that casing member 6 is prevented from turning movement.

The casing portion 6c has windows 61 and 62 arranged above each other and being located in a vertical plane tangential to the cylindrical casing 6c, and to an imaginary cylinder having its vertical axis coinciding with the main axis about which the needle cylinder 30 and the dial ring 32 turn. An adjusting device 100 is disposed at each knitting station of the circular knitting machine, so that all windows 61, 62 of all adjusting devices 100 face outwardly. A scale C is provided on the outer cylindrical surface of ring 4 so that the numbers of scale C consecutively appear in window 62 when knob 1 is turned.

An indicator ring 6a is mounted in a matching circular recess of member 6, and has a set of upwardly projecting teeth or pins 6b arranged in a circle. The outer cylindrical face of indicator ring 6a has a cylindrical scale D which is located under the window 61 so that the numbers of scale D successively appear in window 61 when indicator ring 6a turns.

Carry-over means connect the turnable member 3, 4 with the indicator ring 6a to effect a stepwise movement of indicator ring 6a after each full revolution of turnable member 3, 4 together with turnable member 5.

The carry-over means include a pinion 8 mounted for turning movement on a pin 7 which has a portion secured to the annular member 6. Pinion 8 has teeth 8a longer in axial direction, and teeth 8b shorter in axial direction which are alternately arranged. Knob 1 has an inner cylindrical surface 1b on which a pair of longer teeth 8a slides in the position of FIG. 3a during turning movement of knob 1. The shorter teeth 8b are shorter in axial direction so that they do not extend into the region of the recess having the circular surface 1b.

The circular surface 1b has a single recess 1b', and a pair of pins 1e located on opposite sides of recess 1b', but extending into the region of the shorter teeth 8b.

When knob 1 is turned, a pair of teeth 8a will slide on the inner circular surface 1b until the leading pin 1e engages the shorter tooth 8b located between the respective teeth 8a. Pinion 8 will start turning and the trailing longer tooth 8a will turn to a position passing with its upper part into the single recess 1b'. Further turning of knob 1 will result in further turning of pinion 8 until the respective tooth 8a passes out of recess 1b' and is now the leading tooth sliding on the inner surface 1b, while the next following tooth 8a trails and also slides on the inner surface 1b. In this position, turning of knob 1 can be continued for a complete revolution while pinion 8 is prevented from angular displacement by the pair of longer teeth 8a which slide on the inner surface 1b of knob 1, until the pins 1e and the recess 1b' again become effective.

The shorter teeth 8b of pinion 8 mesh with the pins 6b of the indicator ring 6a. Consequently, ring 6a is turned one step every time the pinion 8 is turned one step, so that the next following indicia of the scale D appears in window 61.

As a result, scale D will indicate in window 61 complete revolutions of knob 1, which preferably corresponds

to distance units, for example millimeters of carrier 35, 37, and of the cams 34a and 34b. Scale C will indicate fractions of the distance units, or turning angles of knob 1.

The adjusting and indicating device 51 for the dial cams is shown in FIGS. 5 and 6. A bushing 18 has a threaded portion 18a tightly screwed into the dial cap 46. The threaded bolt 13 threadedly engages an inner thread 18b on bolt 13 so that turning of bolt 13 will result in axial displacement of screw 47 which is connected to carrier 44 of dial cams 42a, 42b. As explained above, a spring 49 urges screw 47 and thereby the dial cams against the end face of bolt 18.

A knob 12a is secured by a screw 12b to a head portion of bolt 13, and an annular part 12 is secured to the head portion 13a and to knob 12a for turning movement therewith annular member 12 is turnable in a recess in a casing 52, and also surrounds a cylindrical portion of bushing 18. The end face of knob 12a has a circular scale E, as best seen in FIG. 6.

A single pin 16 is secured to the turnable member 12 and cooperates with the teeth 11a of a pinion 11 which is turnably mounted on a pin 17 threadedly secured to a portion casing member 52a of the casing 52. The end face of pinion 11 is covered by a cover plate 14 secured to pin 17 by a screw 15. Cover plate 14 has a window 14a through which a circular scale F on the end face of pinion 11 can be inspected.

When knob 12a is turned, bolt 13 is axially displaced and shifts carrier 44 and dial cam means 42a and 42b in radial direction against the action of spring 49. The angular position of the turnable member 12, 12a, 13 is indicated by the scale E, the valid indicia being the highest on the scale, as shown in FIG. 6, and being indicated by pointer mark 14b on cover plate 14.

After each revolution of knob 12a, pin 16 shifts pinion 11 one step so that another indicia of scale F appears in window 14a to indicate one complete revolution of knob 12a, corresponding to a distance unit of radial adjustment of cams 42a and 42b. Scale E will indicate fractions of the respective distance unit, or angles through which knob 12a has been turned.

Scales F and E are located in parallel vertical planes which are tangential to an imaginary vertical cylinder having its axis coinciding with the vertical axis of the knitting machine.

Referring again to FIG. 1, it will be seen that the scales C, D, E and F all face in the same direction, and are located in parallel vertical planes. Consequently, the operator can read the scale indicia E of the first indicating means, and the scale F of the second indicating means of the adjusting device 51 at the same time he reads the scale indicia C of the first indicating means, and the scale indicia D of the second indicating means of adjusting device 100.

While in the adjusting device 100, the teeth 8a of pinion 8 cooperate with the inner surface 1b to prevent undesired turning movement of pinion 8, pinion 11 in the adjusting device 51 is held in position by the friction exerted by cover plate 14 on the end face of piston 11.

It will be understood that each of the elements described above, or two or more together, may also find a useful application in other types of circular knitting machines including adjustable cam means differing from the types described above.

While the invention has been illustrated and described as embodied in an adjusting and indicating apparatus for the dial cams and cylinder cams of a circular knitting machine and having all scales arranged in an imaginary vertical cylinder for easy observation by the operator, it is not intended to be limited to the details shown, since various modifications and structural changes may be made without departing in any way from the spirit of the present invention.

Without further analysis, the foregoing will so fully reveal the gist of the present invention that others can by

applying current knowledge readily adapt it for various applications without omitting features that, from the standpoint of prior art, fairly constitute essential characteristics of the generic or specific aspects of this invention and, therefore, adaptations should and are intended to be comprehended within the meaning and range of equivalence of the following claims.

What is claimed as new and desired to be secured by Letters Patent is:

1. In a circular knitting machine, in combination, a cylinder cam box having an inner cylindrical surface having an axis; a first carrier movably mounted on said inner surface for movement in axial direction; first cam means mounted on said first carrier and having a first cam track for guiding the butts of cylinder needles surrounded by said cylinder cam box so that movement of said first carrier will influence the position of cylinder needles controlled by said first cam track; a circular dial cap; a second carrier mounted on said dial cap for movement in radial direction; second cam means mounted on said second carrier and having a second cam track for guiding the butts of dial needles so that movement of said second carrier will influence the position of dial needles controlled by said second cam track; and first and second adjusting and indicating devices located in a radial plane passing through said axis, said first device including a stationary member secured to said cam box, and said second device including a stationary member secured to said dial cap, each stationary member having a threaded part, each of said devices including a turnable member having a threaded part threadedly connected to said stationary threaded part, said turnable member being operatively connected to said first or second carriers, respectively, for moving the same; first indicating means fixed to said turnable member for indicating the turning angle of the same; second indicating means turnably mounted on the stationary member; and carry over means connecting said turnable member with said second indicating means and effecting movement of the same after each revolution of said turnable member so that said second indicating means indicates the number of revolutions of said turnable member and distance units, and so that said first indicating means indicates fractions of the distance units whereby the displacement of said first and second cam means is exactly indicated, said first and second indicating means facing in the same direction for simultaneous inspection.
2. In a circular knitting machine, in combination, a cylinder cam box having an inner cylindrical surface having an axis; a carrier movably mounted on said inner surface for movement in axial direction; cam means mounted on said carrier and having a cam track for guiding the butts of cylinder needles surrounded by said cylinder cam box so that movement of said carrier will influence the position of cylinder needles controlled by said cam track; a stationary member secured to said cam box and having a threaded part; a turnable member having a threaded part threadedly connected to said stationary threaded part, said turnable member being operatively connected to said carrier for moving the same; first indicating means fixed to said turnable member for indicating the turning angle of the same; second indicating means turnably mounted on the stationary member; and carry over means connecting said turnable member with said second indicating means and effecting movement of the same after each revolution of said turnable member so that said second indicating means indicates the number of revolutions of said turnable member and distance units, and so that said first indicating means indicates fractions of the distance units whereby the displacement of said carrier and cam means is exactly indicated, said first and second indicating means facing in the same direction for simultaneous inspection.
3. In a circular knitting machine, in combination, a cylinder cam box having an inner cylindrical surface having an axis; a carrier movably mounted on said inner surface for movement in axial direction; cam means mounted

on said carrier and having a cam track for guiding the butts of cylinder needles surrounded by said cylinder cam box so that movement of said carrier will influence the position of cylinder needles controlled by said cam track; a stationary member secured to said cam box and having a threaded part; a turnable member having a threaded part threadedly connected to said stationary threaded part, said turnable member being operatively connected to said carrier for moving the same; first indicating means fixed to said turnable member for indicating the turning angle of the same; a casing member fixedly secured to said cam box; a pinion turnably mounted on said casing member; carry-over means secured to said turnable member for engaging a tooth of said pinion once during each revolution of said turnable member for shifting said pinion one step; and second indicating means including a set of teeth arranged in a circle and meshing with said pinion so that said second indicating means is shifted when said pinion is shifted after each revolution of said turnable member so that said second indicating means indicates the number of revolutions of said turnable member and distance units, and so that said first indicating means indicates fractions of the distance units whereby the displacement of said carrier and cam means is exactly indicated, said first and second indicating means facing in the same direction for simultaneous inspection.

4. A cam adjusting arrangement as set forth in claim 3 wherein said stationary member includes a portion secured to said cam box, said threaded part, and a journal portion; wherein said turnable member includes a knob, a bearing sleeve turnably mounted on said journal portion, and being non-movable in axial direction of said journal portion, and a control ring portion secured to said bearing sleeve for turning movement therewith and having axially extending guide means; and wherein said turnable threaded part has axially extending guide means engaging said guide means of said control ring so that turning of said knob effects turning and axial movement of said turnable threaded part; and wherein said turnable threaded part abuts said carrier to shift the same in one direction; and including biasing means for urging said carrier in the opposite direction.

5. An adjusting arrangement as set forth in claim 4 wherein said casing member includes a cylindrical casing portion formed on one side with a first indicator window cooperating with said first indicating means, and with a second indicator window cooperating with said second indicator means.

6. An adjusting arrangement as set forth in claim 5 wherein said casing member includes an annular part surrounding said bearing portion and being formed with a circular recess; and wherein said second indicating means includes an indicator ring turnably mounted in said circular recess adjacent said cylindrical casing portion and having on the outer surface thereof a scale cooperating with said second indicating window.

7. An adjusting arrangement as set forth in claim 4 wherein said pinion has a set of first teeth longer in axial direction thereof, and a second set of teeth alternating with said longer teeth and being shorter than the same; wherein said knob has an inner circular surface formed with a single recess cooperating with said longer teeth; and a pair of pins secured to said knob and located on opposite sides of said single recess and cooperating with said shorter teeth to turn said pinion to a position in which one of said longer teeth engages said single recess, said pins and single recess being operative once during each revolution of said knob in one position of the same, while in the other turned positions of said knob, a pair of said longer teeth slides on said inner circular surface of said knob to prevent turning movement of said pinion.

8. An adjusting arrangement as set forth in claim 4 and including a spring-loaded member abutting said turnable threaded part at a point diametrically opposite said carrier to prevent binding of said turnable threaded part.

9. In a circular knitting machine, in combination, a cylinder cam box having an inner cylindrical surface having an axis; a carrier movably mounted on said inner surface for movement in axial direction; cam means mounted on said carrier and having a cam track for guiding the butts of cylinder needles surrounded by said cylinder cam box so that movement of said carrier will influence the position of cylinder needles controlled by said cam track; a stationary member secured to said cam box and having a threaded part and a journal portion; a turnable member including a turnable threaded part threadedly connected to said stationary threaded part and abutting said carrier, said turnable threaded part having axially extending guide means, a knob, a bearing sleeve turnably mounted on said journal portion and being non-movable in axial direction of the same, and a control ring having axially extending guide means engaging said guide means of said turnable threaded part so that turning of said knob effects turning and axial movement of said turnable threaded part; first indicating means fixed to said turnable member for indicating the turning angle of the same; second indicating means turnably mounted on the stationary member; and carry-over means connecting said turnable member with said second indicating means and effecting movement of the same after each revolution of said turnable member so that said second indicating means indicates the number of revolutions of said turnable member and distance units, and so that said first indicating means indicates fractions of the distance units whereby the displacement of said carrier and cam means is exactly indicated, said first and second indicating means facing in the same direction for simultaneous inspection.

10. An adjusting arrangement as set forth in claim 9 wherein said turnable threaded part moves said carrier in one direction, and including a spring means mounted on said cam box and urging said carrier in the opposite direction.

11. In a circular knitting machine, in combination, a cylinder cam box having an inner cylindrical surface having an axis; a carrier movably mounted on said inner surface for movement in axial direction; cam means mounted on said carrier and having a cam track for guiding the butts of cylinder needles surrounded by said cylinder cam box so that movement of said carrier will influence the position of cylinder needles controlled by said cam track; a stationary member secured to said cam box and having a threaded part and a journal portion; a turnable member including a turnable threaded part threadedly connected to said stationary threaded part and abutting said carrier, said turnable threaded part having axially extending guide means, a knob, a bearing sleeve turnably mounted on said journal portion and being non-movable in axial direction of the same, and a control ring having axially extending guide means engaging said guide means of said turnable threaded part so that turning of said knob effects turning and axial movement of said turnable threaded part; first indicating means fixed to said turnable member for indicating the turning angle of the same; a casing member fixedly secured to said cam box; a pinion turnably mounted on said casing member; carry-over means secured to said turnable member for engaging a tooth of said pinion once during each revolution of said turnable member for shifting said pinion one step; and second indicating means including an indicator ring having a scale and a set of pins arranged in a circle and meshing with said pinion so that said second indicating means is shifted when said pinion is shifted after each revolution of said turnable member so that said second indicating means indicates the number of revolutions of said turnable member and distance units, and so that said first indicating means indicates fractions of the distance units whereby the displacement of said carrier and cam means is exactly indicated, said first and second indicating means having in the same direction for simultaneous inspection.

12. An adjusting arrangement as set forth in claim 11 wherein said pinion has a set of first teeth longer in axial direction thereof, and a second set of teeth alternating with said longer teeth and being shorter than the same; wherein said knob has an inner circular surface formed with a single recess cooperating with said longer teeth; and a pair of pins secured to said knob and located on opposite sides of said single recess and cooperating with said shorter teeth to turn said pinion to a position in which one of said longer teeth engages said single recess, said pins and single recess being operative once with each revolution of said knob in one position of the same, while in the other turned positions of said knob, a pair of said longer teeth slides on said inner circular surface of said knob to prevent turning movement of said pinion.

13. In a circular knitting machine, in combination, a circular dial cap; a carrier mounted on said dial cap for movement in radial direction; cam means mounted on said carrier and having a cam track for guiding the butts of dial needles so that movement of said carrier will influence the position of dial needles controlled by said cam track; a stationary member secured to said dial cap and having a threaded part; a turnable member having a threaded part threadedly connected to said stationary threaded part and being operatively connected to said carrier for moving the same; first indicating means fixed to said turnable member for indicating the turning angle of the same; a casing member fixedly secured to said cam box; a pinion turnably mounted on said casing member and including second indicating means in the form of a

30
25
20

scale; a stationary cover secured to said casing member and having a window located on said scale; carry-over means secured to said turnable member for engaging a tooth of said pinion once during each revolution of said 5 turnable member for shifting said pinion one step whereby said second indicating means indicates the number of revolutions of said turnable member and distance units, and so that said first indicating means indicates fractions of the distance units whereby the displacement of said 10 carrier and cam means is exactly indicated, said first and second indicating means facing in the same direction for simultaneous inspection.

14. An adjusting arrangement as set forth in claim 13 and including a manually operated knob having a circular 15 face with a circular scale constituting said first indicating means, said knob being secured to said turnable member for turning movement therewith.

15. An adjusting arrangement as set forth in claim 13 wherein said scale is located on one end face of said 20 pinion; and wherein said cover is a plate covering said end face.
